(57) CLAIM

The ornamental design for a dogleg stock, as shown and described.

DESCRIPTION

FIG. 1 is a perspective view of a dogleg stock in accordance with a preferred embodiment of the present invention; FIG. 2 is a top view of the dogleg stock as shown in FIG. 1; FIG. 3 is a right side view of the dogleg stock as shown in FIG. 1;

FIG. 4 is a rear view of the dogleg stock shown in FIG. 1; FIG. 5 is a front view of the dogleg stock as shown in FIG. 1;

FIG. 6 is a left side view of the dogleg stock as shown in FIG. 1; and,

FIG. 7 is a bottom view of the dogleg stock as shown in FIG. 1.

The broken lines are for illustrative purposes only and form no part of the claimed design.
